CARD FILING SYSTEM

John Iuculano, Woodside, N. Y.

Application October 17, 1942, Serial No. 462,335

6 Claims. (Cl. 129—16)

This invention relates to card filing system.

An object of this invention is to provide a card filing system comprising a support and a plurality of holders, with means on each holder to support a plurality of cards arranged in echelon, the arrangement being such that the holders may be individually removed from the support and the cards may be individually removed from the holders.

A further object of this invention is to provide in a card filing system of the character described improved means for supporting the cards on the holder to insure equal spacing of the cards.

Still another object of this invention is to provide a strong and durable card filing or registering device of the character described which shall be relatively inexpensive to manufacture, easy to manipulate and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a front elevational view of a card filing or registering device embodying the invention;

Fig. 2 is an end elevational view of the structure shown in Fig. 1;

Fig. 3 is a cross-sectional view taken on line 3—3 of Fig. 4;

Fig. 4 is an enlarged partial front elevational view of one of the card holders; and

Fig. 5 is a top plan view of the structure shown in Fig. 4 taken on plane marked 5—5.

Referring now in detail to the drawings, 10 designates a card filing system embodying the invention. The same comprises a bottom support 11, a plurality of card holders 12 mounted thereon and each supporting a plurality of cards 13.

Bottom support 11 may be made of wood, metal, composition or any other suitable material and is generally rectangular in shape. It is formed in its upper surface with a plurality of parallel grooves or slots 15 preferably extending the entire length of said support. The grooves are preferably equally spaced apart. They may be spaced apart about $\frac{1}{4}$ of an inch and each groove may be about $\frac{1}{8}$ of an inch in width. These dimensions however may be varied. The support

11 may be placed in a drawer of a filing cabinet or in any other suitable box or cabinet.

The card holders 12 are mounted on the support 11 with the bottom edge of each card holder engaged in one of the grooves 15. The card holder 12 comprises a flat board 17 of fiber board, heavy card board or any other suitable material. It has a length substantially the same as the length of the bottom support 11. Attached to the end edge 18 of the board 17 are reinforcing members 19. Members 19 may be made of wood and each is formed on the inner side thereof with a groove 20 to receive the edge portion 18 of the board 17. Members 19 may be fixed to the board 17 by the use of glue or in any other suitable manner.

The lower edge 23 of the board 17 extends below the lower edges 19a of members 19. The upper ends 19b of members 19 extend above the upper edge of board 17. It will be noted that the lower edge 23 of board 17 of each holder engages within one of the grooves 15. Attached to the upper edge of board 17 is an elongated strip 30 of transparent sheet material, said strip being co-extensive with the board 17 and the outer ends of said strip being received within the groove 20. It will be noted that the strip 30 extends above the upper edge of board 17. The rear face of board 17 adjacent the upper edge thereon may be grooved as at 31 to receive the lower edge portion of strip 30. Strip 30 may be attached to the board 17 by means of any suitable adhesive. Opposite to one end of strip 30 is a label 33 which may have marked thereon a letter, number or other indicia to indicate the class of cards 13 mounted on the holder 12. It will be noted that the upper edge 30a of strip 30 is substantially about the height of the member ends 19.

Attached to the front face of board 17 is an elongated, flat strip 40 of metal or any other suitable material. The lower edge 41 of strip 40 is substantially on the lower ends of members 19. The strip 40 is co-extensive with the boards 17 and the ends thereof may be received within the grooves 20 in members 19. The strip 40 may be attached to the board 17 by means of adhesive or any other suitable material.

Extending forwardly from the lower edge of strip 40 are a plurality of equally spaced hooks 42. The distances between the hooks 42 are preferably the same.

The cards 13 are each formed with a plurality of notches 13a in the lower edges thereof. The notches are equally spaced apart. The distances 55 between the hooks 42 are preferably a multiple

of the distances between the notches 13a. With this construction the cards may be arranged in echelons. The hooks 42 are received in registering notches 13a. The upper corners 45 of the cards may be cut away if desired to expose the label 33. It will now be understood that the card 13 may be individually removed and also that the holders 12 may be individually removed from the support 11.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A card holder comprising a board, a pair of grooved members receiving the upper edges of said board, the lower edge of the board extending below the lower ends of said grooved members, the upper ends of said grooved members extending above the upper edge of said board, a transparent strip attached to the upper edge of said board and extending above said upper edge, a strip attached to the board and disposed above the lower edge of said board, said last strip being formed with a plurality of forwardly extending equally spaced hooks.

2. A card holder comprising a board, a pair of grooved members receiving the upper edges of said board, the lower edge of the board extending below the lower ends of said grooved members, the upper ends of said grooved members extending above the upper edge of said board, a transparent strip attached to the upper edge of said board and extending above said upper edge, a strip attached to the board and disposed above the lower edge of said board, said last strip being formed with a plurality of forwardly extending equally spaced hooks, and a plurality of cards formed with notches in their lower edges mounted on the holder and receiving said hooks, the distances between said hooks being multiples of the distances between said notches.

3. A card holder comprising a board, reinforcing members attached to the outer edges of said board, a strip attached to the front face of said board and above the lower edge of said board, said strip being formed integrally at the lower edge thereof with, forwardly extending, equally spaced tabs.

4. A card holder comprising a flat rectangular board, a pair of grooved members receiving the end edges of said board, the lower ends of said grooved members being spaced above the lower edge of said board and the upper ends of said grooved members extending above the upper edge of said board, and a strip attached to the front face of said board, the lower edge of said strip being spaced above the lower edge of said board and said strip being formed with a plurality of forwardly extending equally spaced tabs.

5. A card holder comprising a flat rectangular board, a pair of grooved members receiving the end edges of said board, the lower ends of said grooved members being spaced above the lower edge of said board and the upper ends of said grooved members extending above the upper edge of said board, a strip attached to the front face of said board, the lower edge of said strip being spaced above the lower edge of said board and said strip being formed with a plurality of forwardly extending, equally spaced tabs, and a plurality of cards mounted on said holder in echelon manner, said cards being formed with equally spaced apart notches to receive said tabs.

6. A card holder comprising a flat rectangular board, a pair of grooved members receiving the end edges of said board, the lower ends of said grooved members being spaced above the lower edge of said board and the upper ends of said grooved members extending above the upper edge of said board, a strip attached to the front face of said board, the lower edge of said strip being spaced above the lower edge of said board and said strip being formed with a plurality of forwardly extending equally spaced tabs, and a transparent strip attached to the upper edge of said board, said board being grooved to receive the lower edge of said transparent strip, said transparent strip extending above the upper edge of said board.
